(57) **CLAIM**

The ornamental design for a building controller touchscreen with control icon, as shown and described.

DESCRIPTION

FIG. 1 shows a first embodiment of a building controller touch screen displaying a control icon;
FIG. 2 shows a second embodiment of a building controller touch screen displaying a control icon;
FIG. 3 shows a third embodiment of a building controller touch screen displaying a control icon;
FIG. 4 shows a fourth embodiment of a building controller touch screen displaying a control icon;
FIG. 5 shows a fifth embodiment of a building controller touch screen displaying a control icon;
FIG. 6 shows a sixth embodiment of a building controller touch screen displaying a control icon; and,
FIG. 7 shows a seventh embodiment of a building controller touch screen displaying a control icon.
The broken line in each of FIGS. 1-7 represent a boundary of the building controller touch screen, and form no part of the claimed design.

1 Claim, 7 Drawing Sheets
